UNITED STATES PATENT OFFICE.

WILLIAM W. HANLON, OF BARNESVILLE, OHIO.

DESIGN FOR A FAN.

SPECIFICATION forming part of Design No. 32,911, dated July 3, 1900.

Application filed May 3, 1900. Serial No. 15,415. Term of patent 3½ years.

To all whom it may concern:

Be it known that I, WILLIAM W. HANLON, a citizen of the United States, residing at Barnesville, in the county of Belmont and State of Ohio, have invented a certain new and useful Design for Fans, of which the following is a specification, reference being had therein to the accompanying drawings.

My invention relates to a certain design for fans adapted for campaign, electioneering, or advertising purposes, the object being the provision of a fan which will present an ornamental and attractive appearance and which will be useful for the purpose designed.

To attain the desired object, my invention consists of a fan of shield shape having the front and rear or reverse sides ornamented to render the fan of beautiful appearance.

Figure 1 represents a front view of my fan, and Fig. 2 represents a view of the back or reverse side.

My fan A is of shield shape, and upon the front is the shield B, having a flag inclosed in the border, and to each side are the flags C, and inclosed by the flags is the rectangular panel D. Directly below the panel is an ornamental inclosure E, in which is an eagle F. Below the eagle is a circular inclosure G, and

on each side of the inclosure E is a pictorial representation of an ocean steamer H and a train of cars J, below which representations are the inclosures K and L, in which are pictorial representations M of a series of factories and N of a farm, the general idea of 35 the representations being peace, prosperity, and happiness.

On the back or reverse side of the fan at the top is the horizontal panel O, below this the curved or segmental panel P, and below 40 the panel P are the vertically-disposed panels Q, and under the panels Q are the eagles R, each having in its beak the banner S, and at the top of the fan is the clover and banner ornamentation T.

It is evident that I provide a design for fans which is of ornamental and attractive appearance and which fan is practical and useful for the intended purpose.

I claim—

The design for a fan, as herein shown and described.

In testimony whereof I affix my signature in presence of two witnesses.

WILLIAM W. HANLON.

Witnesses:

W. M. MOORE,
H. P. HURST.
